REFRIGERATING APPARATUS

Nelson J. Smith, Dayton, Ohio, assignor to General Motors Corporation, Dayton, Ohio, a corporation of Delaware

Application January 31, 1935, Serial No. 4,336

7 Claims. (Cl. 62-2)

This invention relates to refrigerating apparatus and more particularly to air conditioning.

Air conditioning has increased in popularity within recent years. However, in most cases the air temperature within the building, room, or enclosure has been maintained constant by an ordinary thermostat control while the temperature without fluctuated. It has been found that under these conditions on an extremely warm day there is a considerable shock to the person when leaving an air conditioned building, room or enclosure because the difference in temperature is sometimes of the order of 20° or more. For example, in many cases the thermostat is set so as to maintain a room temperature of about 75° F. When the temperature without rises to 95 or 100° F. there is experienced a sudden temperature change of 20 to 25° F. when leaving the air conditioned room or building. This frequently causes some people to feel sick. The ideal condition is to have a minimum temperature of 72° F. in the room and as the outside temperature of the air rises above 70° to have a progressively greater temperature difference between the outside air and the air within the air conditioned room or building. For example, when the outside temperature is 80° F. it is desirable to have a room temperature of about 75° F. while when the outdoor temperature is 95° F. it is desirable to have an indoor temperature of about 80° F.

It is an object of my invention to provide an air conditioning system which will maintain the proper temperature conditions within a room according to the outside temperature so that no sickness or shock will result from passing into or out of the air conditioned room or building.

It is a further object of my invention to provide an improved control means for an air conditioning system responsive to both indoor and outdoor temperatures to maintain the proper temperature differential between the indoor and outdoor temperatures.

Further objects and advantages of the present invention will be apparent from the following description, reference being had to the accompanying drawing, wherein a preferred embodiment of the invention is clearly shown.

In the drawing:

The figure is a diagrammatic illustration of an air conditioned building having air conditioning apparatus embodying my improved control means responsive both to indoor and outdoor temperatures for maintaining the proper differential in

temperatures between the outdoor air and the air within the room.

Referring now more particularly to the drawing, there is shown a building 20 provided with a room 22 to be conditioned and provided with a basement room 24 where there is located a refrigerant liquefying apparatus generally designated by the reference character 26. The refrigerant liquefying apparatus 26 comprises a compressor 28 for compressing the refrigerant and for forwarding the compressed refrigerant to a condenser 30 where the compressed refrigerant is liquefied and collected in a receiver 32. From the receiver the liquid refrigerant is forwarded through a supply conduit 34 to an air conditioning unit 36 located within the room 22 to be conditioned.

This air conditioning unit 26 contains an expansion valve 38 which controls the flow of liquid refrigerant from the liquid line 34 to an evaporating means 40 also located within the air conditioner 36. The operation of the valve 38 is controlled by a thermostat 42 located near the outlet of the evaporator 40 in order to permit a proper supply of liquid refrigerant to be fed into the refrigerant evaporator 40. A motor driven fan 44 is provided in the upper portion of the air conditioner for drawing in air from the room through the opening 46 in the lower portion of the cabinet over the surfaces of the evaporator 40 and discharging the air out through the opening 48 in the top of the air conditioner. A pan 50 is provided in the bottom of the air conditioner beneath the evaporator 40 for collecting any moisture condensed from the air upon the surfaces of the evaporator.

The evaporator 40 evaporates the liquid refrigerant and absorbs heat from the air which is circulated through the air conditioner by the motor driven fan 44. The evaporated refrigerant is returned to the compressor through the return conduit 52. The compressor 28 is driven by an electric motor 54 which is connected by electrical conductors 56 to a source of electric energy designated by the reference character 58. The motor driven fan 44 is also connected to the source of electric energy by the electrical conductors 60 under the control of a switch 62. Heretofore, the operation of such a refrigerating system has been controlled by a thermostat 50 responsive to the temperature of the room 22. However, such a control does not take into account changes in outside temperature which, of course, fluctuate rapidly throughout an ordinary summer day. As before stated, under such

conditions the temperature difference between the outside air and the air in the room may become too great when the outside temperature rises rapidly to a rather high temperature such as 98 or 100° F. or more.

It has been determined that the most desirable temperature regulation would be one which would control the temperature of the room in accordance with changes in outside temperature 10 with a minimum temperature in the room of about 72° F. For example, when the outside temperature is 70° F. the room temperature should be 72° F. When the outside temperature is 80° F. the inside temperature should be about 75° F. When the outside temperature is about 95° F. then the room temperature should be about 80° F. However, this sort of temperature regulation cannot be accomplished by ordinary automatic control which heretofore have been used 20 for air conditioning.

In order to provide an automatic control which is capable of maintaining such a variable differential between the outdoor temperature and the room temperature, I have provided a peculiar 25 form of pressure responsive switch generally designated by the reference character 70 which is connected in the electric circuit 56 in series with the compressor driving motor 54. This switch is provided with two bellows, each having 30 an effective area of about one square inch, one designated by the reference character 72 and the other designated by the reference character 74. These bellows have their upper ends fastened to and fixed to a flange 76 forming the upper portion 35 of the switch 70. This fixed upper end of the bellows 72 is connected by a tube 78 to a thermostat bulb 80 located in contact with the air in the room. The bellows 74 is connected by a tube 82 to a thermostat bulb 84 located outside the building in contact with the outdoor air. The two bellows are connected to the opposite arms 86 and 40 88 of a T-shaped double bell crank lever which is pivoted upon the pin 90 to the base 92 of the switch 70. The other arm 94 of the bell crank 45 lever has a forked or slotted lower end which receives a pin 96 protruding from a sealed mercury tube support 98 which is pivoted upon the pin 102 also extending from the base 92. The upper portion of this pivotal support 98 holds a 50 sealed glass or silica tube 104 containing mercury and a pair of switch contacts at its right end. These switch contacts are connected into the electric circuit 56.

When the pivotal support 98 moves in a clockwise direction about its pivot pin 102 from the position shown in the figure, the mercury within the tube flows to the right end of the tube and completes the circuit across the contacts. When the mercury tube is in the position shown in the 55 figure or to the left of the position shown in the figure, the mercury is not in contact with the contacts and the electric circuit 56 remains open.

In the preferred embodiment I fill the thermostat 60 80 and the bellows 72 with ammonia and I fill the thermostat 84 and the bellows 74 with butane. When the outdoor temperature is 70° F. the butane exerts a pressure of 17 lbs. When the temperature within the room is 72° F. the ammonia exerts a pressure of about 119 lbs. Under 65 such conditions when the outdoor temperature is 70 and the indoor temperature is 72°, it is not necessary to change the temperature of the air within the room since this is the desired temperature. Therefore, it is necessary to interpose a 70 spring or some other means of sufficient force to

counteract the excess force of the ammonia bellows 72. In order to do this I provide a spring retainer 106 connected to the lower end of the ammonia bellows 72 which holds the upper end of a coil spring 108. The lower end of this coil spring is held by a low spring retainer 110 which is held by a screw 112 which is used for adjusting the tension of this spring 108. This spring is preferably adjusted to provide a force of about 102 lbs. and under such conditions causes the switch to 10 assume the position shown in the drawing.

Should the indoor temperature rise, without a change in the outdoor temperature, the ammonia bellows 72 will expand causing the bell crank lever to turn in a counter-clockwise direction about its pivot pin 90 to thereby cause the mercury tube to be tilted to the right so as to close the contacts to the compressor driving motor which will supply refrigeration to the room. However, should the outside temperature rise to 80° and the indoor 15 temperature rise to 75° the switch will still remain substantially in the position shown in the drawing since then the vapor pressure of the butane would rise to 23 pounds while the ammonia pressure would rise approximately the same amount to 126 lbs. Thus the pressure of the butane plus the spring pressure would equal the ammonia pressure. Similarly when the outdoor temperature is 95° F. and the indoor temperature is 80° F. the vapor pressure of the butane will rise to about 30 33½ lbs. while the vapor pressure of the ammonia will rise about the same amount to 138 lbs. This will cause the switch to remain substantially in the position shown. Thus when the proper temperature differential between the outdoor air and the room is maintained the switch remains in the "off" position. However, when this temperature differential becomes less than this desired temperature differential the air conditioning unit 35 supplies refrigeration to the room.

While I have disclosed ammonia and butane as the controlling mediums in my preferred embodiment, others may be selected to provide substantially the same or even different temperature conditions if desired.

In selecting the volatile fluids or refrigerants for the two bellows and their thermostats, it is necessary in order to maintain the desired conditions heretofore described that the increase in pressure of the volatile fluid in the thermostat and bellows responsive to the outside temperature between the temperature of 70° F. and 95° F. be approximately equal to the increase in pressure of the volatile fluid within the bellows and thermostat bulb responsive to the inside temperatures 55 between the temperatures of 72° F. and 80° F. Instead of ammonia and butane as fluids for the bellows and their thermostats, methyl chloride may be used for the inside thermostat and its bellows while ethyl chloride may be used for the 60 outside bellows and its thermostat since their increases in pressure under the ideal conditions are about equal. Likewise, mixtures of volatile fluids may be used to obtain the same results such as a mixture of propane and methyl chloride in 65 the inside thermostat and its bellows and of a mixture of ethyl chloride and butane in the outside thermostat and its bellows. This result may likewise be accomplished by employing additional thermostat control devices, by providing a variable spring tension or resistance, by changing the leverage between the bellows, and by changing the size and effective area of the bellows.

In order to obtain different conditions other volatile mediums may be used in the thermostat 70

bulbs and their bellows or such different conditions may be accomplished by mechanical modifications of the switch device such as by employing additional thermostatic members, different leverages, variable spring tensions, and by varying the effective area of the bellows.

5 While the form of embodiment of the invention as herein disclosed constitutes a preferred form, it is to be understood that other forms might be adopted, all coming within the scope of the claims 10 which follow.

What is claimed is as follows:

1. Refrigerating apparatus including an enclosure containing a medium, means for changing the temperature of said medium, and opposed means rigidly connected together in direct opposition to each other, one responsive to the temperature of the medium and the other responsive to the temperature outside of said enclosure for regulating said means for changing the temperature of the medium, one of said temperature responsive means having a fluid with a high vapor pressure and the other having a fluid with a lower vapor pressure, and spring means 25 opposing the temperature responsive means having the higher vapor pressure fluid.

2. A temperature regulating system for providing a temperature differential between a first medium having a fluctuating temperature and a second medium to be maintained at a predetermined varying temperature differential with respect to the first medium, including means in heat exchange relation with said second medium to be controlled for changing its temperature, means for controlling said means to maintain a progressively varying temperature differential between the two mediums including a temperature responsive power means responsive to the temperature of the first medium, a second temperature responsive power means responsive to the temperature of the second medium, the rate of change in power of the temperature responsive means being proportional to the change in temperature of the first medium and the corresponding desired change in temperature of the second medium, the difference in the rate of change in power of the two temperature responsive means being proportional to the predetermined varying temperature differential, said temperature responsive means being rigidly connected together in direct opposition to each other and being provided with means to control said means in heat exchange relation with said second medium.

3. A temperature regulating system for providing a temperature differential between a first medium having a fluctuating temperature and a second medium to be maintained at a predetermined varying temperature differential with respect to the first medium, including means in heat exchange relation with said second medium to be controlled for changing its temperature, means for controlling said means to maintain a progressively varying temperature differential between the two mediums including a temperature responsive power means providing power in a predetermined ratio to the temperature of the first medium, a second temperature responsive power means providing power in a different predetermined ratio to the temperature of the second medium, a rigid operating connection connecting said first and second power means, and a switch means connected to and operated by

said rigid connection for controlling said temperature changing means.

4. A temperature regulating system for providing a temperature differential between a first medium having a fluctuating temperature and a second medium to be maintained at a predetermined varying temperature differential with respect to the first medium, including means in heat exchange relation with said second medium to be controlled for changing its temperature, 10 means for controlling said means to maintain a progressively varying temperature differential between the two mediums including a temperature responsive power means providing power in a predetermined ratio to the temperature of the first medium, a second temperature responsive power means providing power in a different predetermined ratio to the temperature of the second medium, a rigid operating connection connecting said first and second power means, a 15 switch means operated by both of said power means through said rigid connection for controlling said temperature changing means and yielding means acting upon said power means for providing a varying temperature differential 20 between the two mediums in addition to the differential provided by said predetermined ratios.

5. Refrigerating apparatus including an enclosure containing a medium, means for changing the temperature of said medium, means to control said means including means responsive to the temperature of the medium in said enclosure, and means responsive to the temperature of a medium outside of said enclosure, said means being rigidly connected together in direct opposition to each other and operable in a predetermined ratio upon said control means, whereby a temperature differential between said mediums can be progressively increased as the temperatures of said mediums increase.

6. A temperature regulating system for providing a temperature differential between two media, including means to vary the temperature of one of the media, means to control the temperature varying means including a first power element providing power in a predetermined ratio to the temperature of a first medium, a second power element providing power in another predetermined ratio to the temperature of a second medium, said power elements being rigidly connected together in direct opposition to each other to provide power to said control means in a ratio equal to the resultant in power of said power elements.

7. A temperature regulating system for providing a temperature differential between two media, including means to vary the temperature of one of the media, means to control the temperature varying means including a first power element providing power in a predetermined ratio to the temperature of a first medium, a second power element providing power in another predetermined ratio to the temperature of a second medium, said power elements being connected to opposite ends of a common pivoted lever and providing power to said lever in an increasing resultant ratio when the temperature of one of said media increases at a greater rate than the other of said media, said lever operating said temperature controlling means to maintain a progressively increasing temperature differential between said media.
